TIME SWITCH ACTUATING DEVICE

Bernard E. Lenehan and G. Wilbur Rosenberger,
Bloomfield, N. J., assignors to Westinghouse
Electric & Manufacturing Company, East
Pittsburgh, Pa., a corporation of Pennsylvania

Application January 20, 1938, Serial No. 185,898

7 Claims. (Cl. 74—568)

The present invention relates to timing devices, with specific reference to a time-controlled actuating device for a switch controlling an electric circuit.

Devices of the general type disclosed herein are commonly used for controlling electric circuits at predetermined times and generally comprise a clock mechanism or electric timing motor, which, through suitable gearing, operates a switch actuating device at an adjustable predetermined time. The switch to be actuated may control a lighting circuit, or effect any desired control.

In devices of this character, however, difficulty has been encountered in providing an adjustable actuating device, which while capable of easy adjustment to predetermine the time of actuation of the switch, must also be sufficiently rugged to retain its adjusted position in spite of vibration, shock or other mechanical stress.

It is an object of the present invention to provide an adjustable time controlled actuating device which is capable of ready adjustment and which is of such rugged construction that when once set to a predetermined position, it will remain in that position under normal conditions, as well as many abnormal conditions.

Other objects of the invention will be apparent from the following description when read in conjunction with the accompanying drawing, in which:

Figure 1 is a schematic view of a time controlled device and a switch to be actuated thereby;

Fig. 2 is a plan view of a disc shown in Fig. 1 upon which the actuating device is to be adjustably positioned;

Fig. 3 is a side view partly in section of the disc shown in Fig. 2; and

Fig. 4 is a plan view of the actuating device;

Fig. 5 is a view in elevation, with parts broken away, of the actuating device in operative position.

Referring more particularly to the drawing, the switch 2 to be controlled is shown by way of example as a tilttable switch of the mercury type having electrodes at each end thereof connected to a circuit 4. It is contemplated that any type of switch suitable for the purpose may be employed and the circuit 4 may be used to control any desired operation.

A timing motor 6 is used to effect the operation of the switch 2. As shown, the motor 6 is a synchronous electric motor and is connected

through a gear train 8 to a gear wheel 10 secured to a rotatable shaft 12.

A disc 14, shown in detail in Figs. 2 and 3, is fixed to the shaft of the gear wheel 10 to rotate therewith, or it may be secured directly to the gear wheel 10. The periphery of the disc 14 is provided with a plurality of notches or recesses 16, and one face of the disc is provided with a circular groove 18. The notches and the groove are used to adjustably and firmly position an actuating member for the switch 2, as hereinafter described.

The actuating device itself comprises a member or arm 20 having one end thereof bifurcated to provide legs 22 and 24. The slot between the legs 22 and 24 is of such width that the arm 20 may be slipped over the edge of the disc 14 at any desired point and the arm is retained in a desired position by means of a bolt 26 extending through the arm 22 with the lower reduced extremity thereof fitting into the circular slot 18 of the disc 14. It should be obvious that by tightening down on the bolt 26, the arm 20 may be retained in a desired position radially of the disc.

A switch engaging pin 28 has one end thereof extending laterally through the legs 22 and 24, and across the slot between them, in such manner that when the arm 20 is secured in position the portion of the pin within the slot snugly seats in one of the notches 16 so that there will be no tendency for the arm 20 to rock about the axis of the bolt 26. The opposite end of the pin projects laterally of the arm 20 in a position to engage the depending arm of the switch 2 to effect a tilting thereof when the wheel 14 brings the pin into engagement with the switch arm.

By means of the construction disclosed, an unusually rugged switch actuating mechanism is provided and has the advantage of retaining its adjusted position in spite of quite severe mechanical stresses imposed upon it.

Quite obviously, modifications may be made in the construction disclosed within the scope of the invention and it is intended that the invention be limited only by the scope of the appended claims.

We claim as our invention:

1. In a switch actuating device, a disc and means for rotatably mounting it, an actuating arm having a bifurcated portion proportioned to embrace the edge of the disc with the arm disposed radially of the disc, an arcuate groove in said disc coaxial therewith, and means extending through one leg of said bifurcated portion

into said groove for releasably clamping the actuating arm to the disc.

2. In a switch actuating device, a disc, and means for rotatably mounting it, an actuating arm having a bifurcated portion proportioned to embrace the edge of the disc with the arm projecting radially therefrom, means extending through one leg of the bifurcated portion into engagement with a face of the disc for adjustably securing the arm to the disc, the edge of said disc being serrated, and means carried by said arm in engagement with said serrated edge.

3. In a switch actuating device, a disc, and means for rotatably mounting it, an actuating arm having a bifurcated portion proportioned to embrace the edge of the disc with the arm projecting radially therefrom, means extending through one leg of the bifurcated portion into engagement with a face of the disc for adjustably securing the arm to the disc, the edge of said disc being notched, and means carried by said arm interfitting with a selected one of said notches.

4. In a switch actuating device, a disc, and means for rotatably mounting it, an actuating arm having a bifurcated portion proportioned to embrace the edge of the disc with the arm projecting radially therefrom, means extending through one leg of the bifurcated portion into engagement with a face of the disc for adjustably securing the arm to the disc, the edge of said disc being notched, and means carried by said arm interfitting with a selected one of said notches, said means comprising a pin extending

35 through a leg of said bifurcated portion and into the bifurcating slot thereof.

5. In a switch actuating device, a disc, and means for rotatably mounting it, an actuating arm having a bifurcated portion proportioned to

40 embrace the edge of the disc with the arm pro-

jecting radially therefrom, means extending through one leg of the bifurcated portion into engagement with a face of the disc for adjustably securing the arm to the disc, the edge of said disc being notched, and means carried by said arm interfitting with a selected one of said notches, said means comprising a pin extending through a leg of said bifurcated portion and into the bifurcating slot thereof, and having a portion extending beyond said arm for engaging a member to be actuated.

6. In a switch actuating device, a disc, and means for rotatably mounting it, an actuating arm having a bifurcated portion proportioned to embrace the edge of the disc with the arm projecting radially therefrom, means extending through one leg of the bifurcated portion into engagement with a face of the disc for adjustably securing the arm to the disc, the edge of said disc being notched, and means carried by said arm interfitting with a selected one of said notches, said means comprising a pin extending through a leg of said bifurcated portion and into the bifurcating slot thereof, and having a portion extending beyond said arm perpendicular to the face of the disc for engaging a member to be actuated.

7. In a switch actuating device, a circular supporting element having a serrated edge, means for rotatably mounting said element, an actuating arm having a bifurcated portion proportioned to embrace the edge of the element, an arcuate groove in said element coaxial therewith, means extending through one leg of said bifurcated portion into said groove for releasably clamping the actuating arm to the element, and means carried by said arm interfitting with the serrations on said element.
